RECORD CONTROLLED INTERPRETING
MACHINE

James W. Bryce, Glen Ridge, N. J., assignor to
International Business Machines Corporation,
New York, N. Y., a corporation of New York

Application June 7, 1941, Serial No. 397,002

10 Claims. (Cl. 101—93)

This invention relates to record controlled interpreting machines, and more particularly to such machines having provisions therein for checking the sensing and recording operations, and detecting failures of the latter operations to correspond to the sensed record designations.

More specifically, the present invention contemplates sensing the coded data designations on the individual records and effecting operations for recording the interpreting data on the related sensed records, as provided for in U. S. Patent No. 1,946,900, and concomitantly, storing and retaining representations of the sensed data, thereby permitting the latter to be compared with the representations of the recorded data, and causing indications of the resultant comparison operations to be effected. The comparison operations, to be described, include the step of eliminating, under control of the operations of the recording means, the retained representations from the storing devices by tending to clear or wipe out these representations from the latter during each operation of the recording means. It will become evident to those skilled in the art, as description herein progresses, that other known comparison and checking methods are contemplated to be encompassed within the scope of this invention.

Accordingly, an object of the present invention resides in the provision of an improved machine wherein manifestations of data are effected in accordance with the data designations sensed on individual records, and wherein the data manifesting operations are checked by determining, first, the identity of the sensed data designations, then determining the identity of the manifested data, and then comparing the representations of the sensed and manifested data to detect and indicate the failure of the manifesting operations to correspond to the sensed data designations.

Another object of the present invention resides in the provision of means for storing representations of the data, and, under control of the sensing means, cause the representations of the sensed data to be stored therein, and then, subsequently, under control of the manifesting means, such as recording or printing means, cause the representations of the recorded data to be entered in the storing means to eliminate or clear out the originally entered representations during the operations of the said recording means, thereby effecting the detection of the failure of the recording operations to correspond to the sensed designations, by virtue of the fail-

ure of eliminating or clearing out entirely the originally entered data representations.

Other objects of the invention will be pointed out in the following description and claims and illustrated in the accompanying drawings, which disclose, by way of example, the principle of the invention and the best mode, which has been contemplated, of applying that principle.

In the drawings:

10 Fig. 1 is a central section of the machine.
Fig. 2 is a sectional view taken at one side of

15 the machine.
Fig. 3 is a view in side elevation disclosing in normal position the means controlled by the type bars for effecting operations of the checking contacts.

15 Fig. 4 is a perspective view of the contact closing devices to show more clearly their arrangement and construction.

20 Fig. 5 is a sectional view of one type of data representation storing and retaining means.

Fig. 6 is a timing chart for certain control elements of the machine.

Fig. 7 is a circuit diagram of the connections 25 of the electrical control elements of the machine.

Fig. 8 is a fragmentary view of a suitable record card.

30 The mechanism disclosed herein for recording the interpreting data on the related sensed record cards is similar to the structure described in the U. S. Patent 1,946,900, consequently, it is considered that the following brief description of the like elements, and their operations, is sufficient to comprehend the instant invention.

35 Record card feeding means

Referring now to Figs. 1 and 2, the mechanism will be described for feeding individually record cards from a stack and transporting the cards successively past the sensing station, then to the recording station where the cards are held stationary, momentarily, during the recording operations, and thence to a card receiving hopper.

45 A main drive shaft 10 is provided, which may be driven in any suitable manner, for example, by a motor M (Fig. 7) and a driving belt 11, which shaft is enabled to drive shaft 15 through the worm gearing 13 and 14. A box cam 16 is 50 secured to shaft 15, which cam actuates the co-operating pivoted cam follower arm 17 and arm 19 through the adjustable connecting rod 20.

Arm 19 is secured to a shaft 21 having arms 22 (one of which is shown in Fig. 1) in pin and slot engagement with card picker 23 mounted for re-

ciprocation in the frame of the machine. By means of the actuated shaft 21 and the reciprocating picker mechanism, record cards are advanced, one at a time, from the supply stack 24.

Through gears 25 (Fig. 2), the shaft 18 drives a parallel shaft 26 which has a threaded section 27 meshing with worm gear 28 on roller shaft 29 to drive continuously the feed rollers 30. The advanced cards are fed, by the said feed rollers, past the record sensing means, comprising the conventional sensing brushes 31 and contact roller 32. After passing the sensing brushes, each card passes to a pair of intermittently driven rollers, comprising an upper spring pressed roller 33 and a lower roller 34. These rollers 33 and 34 advance the cards to a printing station, and then momentarily are paused in their rotation to permit printing on each card in accordance with the preceding analysis.

This interruption in the advancement of the cards is accomplished as follows: Roller 34 is secured to a shaft 35 having attached at one end a gear 36 meshing with an idler gear 36a which in turn meshes with a gear 36b, the latter being secured to shaft 36c. Gear 36b meshes with a gear 37 on shaft 38, on which shaft is also secured a gear 39 driven by a mutilated gear 40 on the continuously rotated shaft 18. Thus, during the rotation of shaft 18, gear 39 will pick up gear 39 to advance each card to printing position, whereupon, at this particular moment in the cycle of operation, the toothless portion of gear 40 moves into locking engagement with gear 39 as shown in Fig. 2. Upon completion of the printing operations, gear 39 is again engaged for rotation, and each card is then fed forward to a conveyor comprising rollers 41 and tracks 42, which convey the cards to a suitable discharge hopper 43. The shafts upon which rollers 41 are secured are continually driven by the gear connections 44 to the shaft 26.

It should be mentioned that a conventional type of card lever is provided between rollers 33 and the sensing station for controlling contacts 30a. These contacts are closed as long as cards are fed from the supply stack, by virtue of the engagement of the cards with the said card lever.

Printing means

For effecting the printing on the record cards, as they successively pass through the machine, a plurality of type bars 45 (Fig. 1) are provided. These bars are all mounted for reciprocation in the frame of the machine, and each have a connection through a spring-pressed pawl 46 to a crosshead 47. Thus, in Fig. 1, upon movement of crosshead 47 to the left, the pawls 46, through frictional engagement with bars 45, will move the bars concurrently in the same direction.

The bars may be arrested at any point in their travel, and subsequently the pawls 46 disengage from, and permit further movement of, the crosshead 47. Upon the reverse movement of crosshead 47, the projecting ends of the bars 45 are engaged thereby to positively move the bars to restored position. For reciprocating crosshead 47 the following mechanism is provided.

In Fig. 2, the crosshead 47 is connected at its ends to blocks 48, slidable upon rods 49, and having pivoted link connections 50 to a follower arm 51 pivoted at 52. Arm 51 has a roller 53 cooperating with the cam groove of a box cam 54 mounted on a shaft 55 connected through worm gear 56 and worm 57 to the constantly running shaft 18. The arrangement and timing of the

parts is such that the type bars 45 are advanced under the influence of pawls 46 synchronously with the movement of a card past the sensing brushes 31.

If a perforation at, say, the 5 position on the card were under the sensing brushes, the corresponding type representing 5 would be at the printing line. The establishment of an electric circuit through the index point perforations by the brushes causes a magnet 58 to be energized. There are a number of these magnets 58 corresponding to the different columns in the card, each magnet being related to a corresponding type bar 45. The energization of any magnet 58 causes the release of a related pawl device 59 through a wire 61 and latch 62, and allows it to engage one of the ratchet teeth 63 on the bar 45. After pawl 59 engages the teeth 63, further movement of the type bar 45 to the left in Fig. 1 is prevented. The type bars 45 are positioned during the passage of a card past the brushes. Subsequently, these type bars are held stationary during the period that a card passes from the analyzing station to printing position, and during the printing operation. After the printing operation, pawls 59 and latches 62 are positively restored in the following manner.

Secured to shaft 55 is a cam 63 (Fig. 1) which cooperates with and actuates an arm 64 pressed upwardly by a spring 65 acting through an arm 66 on shaft 67. The shaft 67 has an arm 68 to which is secured a restoring plate 69, and through connection to a pivoted arm 70 also actuates a restoring plate 71. In this manner, cam 63 moves plate 69 to the left, as viewed in Fig. 1, to restore pawls 59, and plate 71 upwardly to restore latches 62 and their connected wires 61.

From each type bar 45 there is an individual hammer 72 which strikes the particular type 73 on the type bar at the printing line. The hammers are pivotally mounted on a rod 74 carried by a bar 75 and depend for their actuation upon movement of said bar. The bar 75 is pivoted on the frame of the machine, by means of pintles co-axial with rod 75, and has springs 76 biasing the bar in a clockwise direction in Fig. 1. To the middle of bar 75 there is pivoted a cam follower arm 77 bifurcated to straddle shaft 55 and having a roller 77a in cooperation with a cam 78. Fixed to one face of the cam 78 is a cam member 79 which cooperates with a projection 80 of the cam follower arm 77.

As the cam 78 revolves, by virtue of the shaft 55 being driven in the manner previously described, it cooperates with the arm 77 through its follower roller 77a, gradually retracting the hammer 72 in a counterclockwise direction against the tension of springs 76. As the roller 77a leaves the high point of the cam 78, member 79 engages the projection 80, and upon continued rotation of the cam, the projection 80 drops from the member 79, and the springs 76, thus released, turn the common bar 75, in a clockwise direction, to swing the hammers 72 against type 73, thus effecting printing.

In Fig. 1, the reference character 81 designates a printing platen journaled in the frame of the machine and adapted to be turned by frictional engagement with the passing card to prevent excessive wear at any one place. The inking ribbon devices are of conventional form and require no detailed description, the ribbon 82 being guided along the platen 81 and beneath the record card. In Fig. 8, a portion of a perforated record card is shown with the inter-

preting data printed at the top of the card, and disposed at the head of each corresponding perforated column.

It should also be mentioned that a plurality of cam elements 55a (Fig. 2) are provided, and secured to shaft 55, for controlling the operations of the related contacts, such as the contacts CC1 to CC4, CB1, and CB2 (see Figs. 6 and 7). The timing arrangement of the operations of these contacts is shown in Fig. 6.

Checking means

The checking means, referred to hereinabove, for checking the sensing and recording operations, and detecting failures of the latter operations to correspond to the sensed record designations will now be described. This means comprises generally a checking contact unit, and a data storing and retaining unit.

Checking contact unit.—This unit will be described first and, as disclosed herein, is arranged to be under the control of the described printing means. Provision is made, whereby, the operations of the individual contacts of the unit are controlled by the positioned type bars.

With reference now to Figs. 1, 3 and 4, each type bar 45 is provided with a camming lever 85, pivoted at 86 to the crosshead 47, and having a sloping camming portion 87 cooperating with the tail 88 of the pawl 46. When the type bar 45 is positioned to the left, as viewed in Fig. 3, and assuming for the moment, that its travel is unimpeded by pawl 59, the relationship of the positions of these described elements, namely pawl 46, camming lever 85, and type bar 45, is unaltered; however, assume now, that pawl 62 is unlatched, due to the energization of magnet 58, after a short travel of the type bar 45, to permit the pawl 59 to engage a notch 60 to stop the type bar 45, the said relationship referred to is altered upon further advancement or positioning of the crosshead 47, after the typebar is stopped, due to the action of the camming edge 89 and pawl 46. The latter is rocked in a clockwise direction so that the tail 88 in engagement with the portion 87 of lever 85 will rock the lever 85 in a clockwise direction.

Disposed beneath each camming lever 85 are individual T-shaped levers 90 which are carried by a pair of supporting arms 91 loosely mounted on rods 92, the latter being supported by the fixed upright members 93. Now, upon rocking of lever 85 as described, this lever is effective to displace, or position in a downwardly direction, the related T-shaped lever 90. It is to be noted, in Fig. 4, that every other upper and lower arm 91 has integral therewith an extension arm 94, each arm 94 being disposed in close proximity to a related set of contacts 95. These elements are arranged so that the contacts 95 are closed at all times the related T-shaped lever 90 is not acted upon by the camming lever 85, that is, the said contacts are closed at the times the related lever 90 is not displaced, or positioned in a downwardly direction. Whenever the said T-shaped levers 90 are displaced the said extension arms 94 are urged in a counterclockwise direction to open the related contacts 95.

The said operated contacts 95 are restored to their closed positions as shown in Fig. 3, during that period of the machine cycle when the crosshead 47 is returned to restore the differentially displaced typebars to the home position. The closures of the said sets of contacts 95 will occur at differential times in the machine cycle, since

the closures of the said contacts occur, whenever the stopped typebars are picked up by the crosshead, during the return travel of the latter. When the said typebars are picked up by the crosshead, springs 96 and 97 urge the pawls 46, camming levers 85, and T-shaped levers 90, respectively, to the home positions as shown in Fig. 3.

The purpose of contacts 95 will be explained in detail later, but it can be stated at this time, that these contacts exercise controlling functions over the data storing means, during that period in the machine cycle, when the typebars are restored to the home position.

Data storing unit.—The purpose of this unit, in the instant case, is to store or set up representations of the data sensed on the record cards, during the first half period of the machine cycle, and retain this data so that subsequently, in the same cycle, when the typebars are restored to their home positions, this retained data is cleared or wiped out, under control of the typebars, whenever the typebar operations correspond to the sensed data designations.

In order to simplify this description, the data storing unit chosen for illustrative purposes comprises part of the well known data accumulating means disclosed in U. S. Patents 1,965,979 and 1,976,617. Since the accumulation of data values forms no part of the present invention, the usual tens carry or transfer means of the individual denominational order are omitted herein.

Referring now to Fig. 5, one order of this unit is shown to include a clutch element 100 which is slidably mounted on the shaft 101 and keyed for rotation therewith. A clutch element is provided for each order of the storing unit, and is provided with a groove in which fits the end of an arm of a suitably pivoted lever 102. This lever is normally held in the position shown by the armature 103 of magnet 104. Upon energization of the magnet its armature is attracted thereto, thereby releasing the lever 102, which is urged by the leaf spring 105, and causing the clutch element 100 to move into engagement with the cooperating teeth 106 which are integral with gear 107, the latter being loosely mounted on shaft 101. Gear 107, when thus coupled to shaft 101 rotates gear 108 which meshes therewith, and effects displacement of an index wheel 109.

It is to be understood that the magnets may be energized at different points in the machine cycle, depending upon the times at which establishment of the control circuits associated therewith are effected. The energization of these control circuits will be described in conjunction with the circuit diagram. At the end of each data entry cycle a declutching operation is effected by suitable control elements included in the unit and are described in greater detail in the said Patent 1,976,617. The rearward extremity of lever 102 is engaged, by a finger 110 carried on a bar 111, at the end of each entry cycle for disengaging the clutch element 100 from teeth 106, and effecting relatching of the armature 103. With reference to Fig. 6, it is seen that two entry cycles are included in the complete machine cycle, and the declutching operations referred to occur approximately at the 12 and 26 machine cycle points.

Also driven by gear 107 is a gear 112 which is displaced in the same manner as the index wheel. Carried by and insulated from gear 112 is a pair of electrically connected brushes 113, one of which is arranged to engage a single conducting segment 114 at the home position of the brushes,

while the other engages an arcuate conducting strip 115 (also see Fig. 7). The relationship of the parts is such that when the index wheel 100 is in its zero or home position, one of the brushes is in contact with the conducting segment 114, and the other brush is in contact with the strip 115, thus forming an electrical connection between the two. Upon displacement of the said index wheel and brushes, this electrical connection is broken. The said electrical connection between segment 114 and strip 115 forms part of an indicating circuit which will be traced presently.

The driving arrangement for shaft 101 includes a gear 116 (Fig. 2) secured to shaft 10, which gear meshes with gear 117. Integral with the latter is a gear 118 which meshes with gear 119. Secured to gear 118 is a small gear 120 which meshes with gear 121 securely mounted on shaft 122, the latter being the drive shaft of the unit, which is effective to drive shaft 101 through the gearing 123 and 124.

Whenever it is desired to reset the individual index wheels and brushes, a suitable crank member 125 is provided on the reset shaft 126 for manually resetting these elements to the home position in a manner well known in the art.

Machine operations

Starting circuits.—Referring now to Fig. 7, with the line switches S closed, and upon depression of the start key SK, a circuit is completed from conductor 130 to the closed contacts 131 of the start key, coil of relay R1, motor M, to conductor 132, effecting energization of the said relay and motor. A holding circuit for the relay R1 is established immediately upon closure of its contacts R1a, and can be traced as follows: Conductor 130, cam contacts CC1 and CC4, contacts R1a, coil of relay R1 and motor M to conductor 132. Upon energization of the said motor, the described driving connections are set into operation to feed the cards, one at a time, from the supply stack to the sensing and printing stations. Upon advancement of the first and following cards from the supply stack the contacts 30a are closed, as indicated in Fig. 6, to cause energization of relay R2, and consequently the closure of contacts R2a and R2b.

A second holding circuit for relay R1 can now be traced from conductor 130 to the normally closed contacts 133 of the stop key STK, the closed electrical connections through the serially connected brushes 113, conducting segments 114, and conducting strips 115 for the different orders of the data storing means (which for the moment are assumed to be in the home positions as shown), contacts R2a, and R1a, coil of relay R1 and motor M to conductor 132. This circuit shunts the circuit including cam contacts CC1 and CC4, and under the described conditions, would maintain the said relay and motor energized irrespective of the opening of cam contacts CC1 and CC4 at the respective cycle points indicated in Fig. 6. Also as long as cards are fed through the machine, the cam contacts CC4 are shunted by the closed contacts R2a. Thus, the contacts CC1 can be termed testing contacts for testing the circuit conditions of the second described holding circuit. It is noted that the CC1 contacts open near the end of the machine cycle, when the checking operations, which will be described presently, are completed. As long as the electrical connections of the data storing unit are in the closed or home positions as indicated, the operations of the machine are not interrupted.

However, if, during a machine cycle, the said electrical connections were not closed, which would indicate that a non-checking condition would be existing, that is, the brushes 113 would not be in the home positions near the end of this cycle, the operations of the machine would then be interrupted upon the opening of contacts CC1.

Interpreting and checking circuits.—Now, as the cards are advanced to the sensing station, the brushes 31 and conducting roller 32 are effective to complete circuits to the connected printing control magnets 58 at the differential times, in the first half period of the machine cycle, the perforations in the record cards are presented to the said brushes and roller. A typical circuit can be traced from conductor 130 to contacts CB1 (see Fig. 6), contacts R2b conducting roller 32, brush 31, plug connecting conductor 134, magnet 58, and cam contacts CC3 to conductor 132, energizing said magnet at the time in the cycle the perforation is sensed.

In this machine, the cards are fed so that the top edge of the card as shown in Fig. 8, is the leading edge, i. e., the index positions are presented to the sensing station in the 0, 1, 2, 3, etc., order. It was mentioned hereinabove that the type elements of the typebars are advanced to the printing position in timed relationship with the passage of the index point positions past the sensing brushes. Therefore, upon sensing a 2 perforation in one column on the card, the magnet 58 is energized to release the pawl 59 to cause the related typebar to stop with the 2 type element opposite the printing position. Upon sensing all the index point positions, the printing hammers are released to print the interpreting data at the head of the related columns on the card as shown in Fig. 8.

At the same time magnet 58 is energized, during the sensing portion of the machine cycle, a circuit is completed from the said sensing brush to plug connecting conductor 135, contacts R3a and coil of magnet 184, energizing this magnet. Again assuming a 2 perforation being sensed, the magnet 184 is energized at this time in the cycle and advanced eight steps before the mentioned declutching operation is effected. In this manner, the representations of the sensed data are entered into related orders of the data storing unit. These representations can be thought of as the tens complement of the sensed members. Or, if desired, the digit representations usually disposed on the periphery of the index wheels can be arranged in a reverse order, as compared to the usual arrangement of these representations on the wheels in the accumulator means described in Patent 1,976,617. This way the true number would be indicated. For the present invention it is immaterial whether the true number or tens complement of the sensed number is indicated on the index wheels. The reason for this will be understood presently. Since no automatic resetting means are provided in the present data storing unit the index wheels and brushes 113 which are displaced from their home positions remain in the displaced positions, and thus retain therein the entered representations of the sensed data.

Approximately at the 16 machine cycle point (see Fig. 6) the cam contacts CC2 are closed to cause relay R3 to be energized. At this time the R3a contacts are opened and the R3b contacts are closed. Continuing with the assumed example, that one of the typebars is stopped at the

2 position, then, it is understood that the related contacts 95 are opened when the said relay R3 is energized. Now, during the typebar restoring operations, the typebar stopped at the 2 position is picked up at the 24th cycle point of the machine to cause the related contacts 95 to be closed at this time. A circuit can now be traced from conductor 130 to contacts CB2, contacts 95, plug connecting conductor 136, contacts R3b, coil of magnet 104 to conductor 132, energizing said magnet. The related clutch mechanism of this order of the data storing unit is tripped to advance the associated index wheel and brushes 113 two steps, before the mentioned declutching operation is effected, during this portion of the machine cycle. Thus, it is seen that the index wheel and brushes of this order of the data storing unit were advanced ten steps during the two portions of the machine cycle, namely the sensing operation portion, which is the first half and the typebar restoring operation portion, which is the second half, or stated in other words, during the sensing portion of the cycle, the representations of the sensed data are entered in the storing unit, and during the typebar restoring portion of the cycle, the retained data is cleared or wiped out by advancing the index wheels and brushes to the home positions. In this manner, the interpreting operations can be checked to determine whether or not the recording operations and data recorded thereby correspond to the sensed data designations. In the event non-correspondence exists between the sensed and recorded data, the brushes 113 of one or more orders of the storing unit are not returned to the home positions at the end of the machine cycle, and in such cases, the holding circuit for relay R1 and motor M shunting cam contacts CCI cannot be established. Further machine operations are then interrupted, thus, giving an indication of the non-corresponding operations performed by the machine. To resume operations of the machine the brushes 113 of the storing unit are manually reset to the home position, as described hereinabove, and the start key SK once again is depressed.

While there has been shown and described and pointed out the fundamental novel features of the invention as applied to a single modification it will be understood that various omissions and substitutions and changes in the form and details of the device illustrated and in its operation may be made by those skilled in the art, without departing from the spirit of the invention. It is the intention therefore, to be limited only as indicated by the scope of the following claims:

What is claimed is:

1. An interpreting machine controlled by records bearing data designations having means for recording the interpreting data on the related records, means for sensing the data designations on the records, means for feeding the records, one at a time, and transporting them first to the sensing means and then to the recording means, means controlled by the sensing means for controlling the operations of the recording means in accordance with the sensed designations, storing means having control means controlled by the said sensing means for effecting entries of representations therein determined by the sensed designations, means controlled by the recording means for controlling the said control means of the storing means, according to the operations of

5 the recording means, for causing elimination of the entered representations of the sensed designations in the storing means, and means under control of the said storing means for modifying the operations of the said feeding means whenever the recording means fail, during recording operations, to effect elimination of the said entered representations in the storing means.

2. A cyclically operable recording machine controlled by records bearing columns of data designations having recording means, means for sensing the columns of designations on a record during a cycle of operation of the machine, means controlled by the sensing means for controlling the operations of the recording means, during the said cycle, in accordance with the sensed designations, rotatable means, one for each column of data designations sensed, for storing representations of the data, which means normally before the beginning of each cycle, are reset to a home position, said rotatable means having control means controlled by the said sensing means, during the said cycle, for causing the rotatable means to be advanced and effecting entries of the representations in accordance with the sensed designations, means controlled by the recording means for controlling the said control means, at a later time in the cycle, for causing the rotatable means to be advanced further and effecting additional entries of representations therein according to the operations of the recording means thereby tending to reset the rotatable means to the said home position, and means under control of the said rotatable means, for indicating, near the end of said cycle, the failures of the recording means to effect resetting of the said rotatable means to the home position.

3. A cyclically operable recording machine controlled by records bearing data designations having recording means, means for sensing the designations on a record during a cycle of operation of the machine, means controlled by the sensing means for controlling the operations of the recording means, during the said cycle, in accordance with the sensed designations, settable means for storing representations of the data, which means, normally before the beginning of each cycle, are reset to a home position, said settable means having control means controlled by the said sensing means, during the said cycle, for conditioning the settable means and effecting entries of representations therein in accordance with the sensed designations, means controlled by the recording means, during the said cycle, for controlling the said control means, at a later time in the cycle, for conditioning the settable means and effecting additional entries of representations therein according to the operations of the recording means thereby tending to reset the settable means to the said home position, and means under control of the said settable means, for indicating, near the end of said cycle, the failure of the recording means to effect resetting of the said settable means to the home position.

4. A cyclically operable recording machine controlled by records bearing data designations having recording means, means for sensing the designations on a record during a cycle of operation of the machine, means controlled by the sensing means for controlling the operations of the recording means, during the said cycle, in accordance with the sensed designations, storing means having control means controlled by the

said sensing means, during the said cycle, for effecting entries of representations therein determined by the sensed designations, means controlled by the recording means, during the said cycle, for controlling the said control means of the storing means and effecting additional entries therein according to the operations of the recording means thereby causing elimination of the first mentioned entered representations, and means under control of the said storing means, for indicating, near the end of said cycle, the failure of the recording means to effect elimination of the said first mentioned entered representations in the storing means.

5. A recording machine controlled by records bearing data designations having recording means, means for sensing the data designations on the records, means controlled by the sensing means for controlling the operations of the recording means in accordance with the sensed designations, storing means having control means controlled by the said sensing means for effecting entries of representations therein determined by the sensed designations, means controlled by the recording means for controlling the said control means of the storing means, according to the operations of the recording means, for causing elimination of the entered representations of the sensed designations in the storing means, and means under control of the said storing means for indicating the failure of the recording means to effect elimination of the said entered representations in the storing means.

6. An interpreting machine controlled by records bearing data designations having means for recording the interpreting data on the related records, means for sensing the data designations on the records, means controlled by the sensing means for controlling the operations of the recording means in accordance with the sensed designations, checking means including means under control of the sensing means for determining the values of the sensed data during the sensing operations and additional means under control of the recording means for determining the values of the recorded data during the recording operations, and means, under control of the checking means, for indicating the conditions of non-correspondence between the values of the sensed and recorded data as determined by the said checking means.

7. An interpreting machine controlled by records bearing data designations having means for recording the interpreting data on the related records, means for sensing the data designations on the records, means for feeding the records, one at a time, and transporting them first to the sensing means and then to the recording means, means controlled by the sensing means for controlling the operations of the recording means in accordance with the sensed designations, checking means, successively controlled by the sensing and recording means, having means for controlling the operations thereof during the operations of the sensing and recording means for representing the sensed and recorded data and determining whether the said sensed and recorded data

represented by the checking means correspond, and means effective, under control of the checking means, for modifying the operations of the said feeding means when the said sensed and recorded data represented by the checking means fail to correspond.

8. An interpreting machine controlled by records bearing data designations having means for recording the interpreting data on the related records, means for sensing the data designations on the records, means controlled by the sensing means for controlling the operations of the recording means in accordance with the sensed designations, checking means, successively controlled by the sensing and recording means, having means for controlling the operations thereof during the operations of the sensing and recording means for representing the sensed and recorded data and determining whether the said sensed and recorded data represented by the checking means correspond, and means, under control of the said checking means, for indicating the conditions of non-correspondence between the said sensed and recorded data represented by the checking means.

25 9. A data manifesting machine controlled by records bearing data designations having data manifesting means and control means therefor, means for sensing the data designations and controlling the said control means for effecting manifestation of the sensed data, checking means including means under control of the sensing means for effecting the determination of the identity of the sensed data during the sensing operations and storing the representations of the said data and additional means under control of the manifesting means for effecting the determination of the identity of the manifested data during the operations of the manifesting means, the said additional means including means for clearing out the stored data representations whenever the manifesting operations correspond to the sensed designations, and means, under control of the checking means, for indicating the conditions of non-correspondence between the said sensed and manifested data determined by the checking means.

10. A recording machine controlled by records bearing data designations having recording means, means for sensing the data designations on the records, means controlled by the sensing means for controlling the operations of the recording means in accordance with the data sensed, data storing means normally devoid of any data representations, means, successively controlled by the sensing and recording means, for controlling the operations of the storing means for effecting entries of data representations successively therein during the sensing operations and during the operations of the recording means, to determine whether the sensed and recorded data entered in the storing means correspond, and means under control of the storing means for indicating the failures of the recording means for causing the storing means to be devoid of any data representations.

JAMES W. BRYCE.
